INVENTOR.

BY

Stephen Campbell ATTORNEYS.

UNITED STATES PATENT OFFICE.

NANNIE K. HUNT, OF ADOLPHUS, KENTUCKY.

FINGER-RING AND PHOTO-MOUNT FOR THE SAME.

1,362,995.

Specification of Letters Patent. Patented Dec. 21, 1920.

Application filed July 31, 1920. Serial No. 400,438.

To all whom it may concern:

Be it known that I, NANNIE K. HUNT, a citizen of the United States, residing at Adolphus, in the county of Allen and State 5 of Kentucky, have invented certain new and useful Improvements in Finger-Rings and Photo-Mounts for the Same, of which the following is a specification, reference being had therein to the accompanying drawings.

10 This invention relates to finger rings and it has for its object to provide a device adapted to be worn upon the finger, in the usual way, and provided with a photo receiving recess and a transparent cover for 15 the same whereby the photograph of a loved one, or of a political or other celebrity, may be worn upon the hand.

Like reference characters designate corresponding parts in both of the figures of 20 the drawing.

Referring to the drawing; Figure 1 is a plan view of a ring constructed in accordance with the invention with the lid of the 25 picture receiving compartment in open position;

Fig. 2 is a magnified sectional view through a part of said ring and Fig. 3 is an enlarged sectional view illustrating a locking device hereinafter described.

30 In the drawing 5 designates the body portion of the ring that is adapted to embrace the finger. This body portion is enlarged at 6 to form a flat channeled portion 7 having the overhanging walls 8 along three sides, 35 the fourth side of said channel being open at 9, so that a picture may be slipped thereinto, when the lid or cover 10 is in open position. This lid or cover comprises a rectangular framework 11, which carries a 40 glass panel 12. A downturned rib 13 of the frame 11 is hinged at 14 to the body portion 6 of the ring and forms a closure for the fourth or open side of the channel recess 7, when the lid or cover is in closed position.

45 To provide means for locking the lid or cover in closed position and for having the

locking means concealed from view and in position where it will not scratch or otherwise injure the person wearing the ring, I provide a latch 15 that is secured to the 50 frame 11, at 16, by soldering or otherwise. This latch has a beveled nose 17 that is adapted to snap past a beveled projection 18 at one side of the channeled portion 7, to hold the lid in closed position. This construction provides an exceptionally tight 55 joint and one that will be quite ornamental.

It is to be understood that the invention is not limited to the precise construction set forth but that it includes within its purview 60 whatever changes fairly come within either the terms or the spirit of the appended claims.

Having described my invention, what I 65 claim is:

1. A device of the character described comprising a finger embracing band having an enlarged top portion, channels along three of its sides and open at the fourth side, a cover comprising a rectangular frame, a glass panel carried by said frame, means for hinging said frame to the said channeled member and a detent between the free edge of the lid and the body of the ring. 70

2. A device of the character described 75 comprising a finger embracing body portion, channels to form a picture receiving recess with overhanging walls along three of its sides and open at the fourth side, a frame comprising a rectangular member, a transparent panel carried by said rectangular member, a rib upon the rectangular member closing the fourth side of the channel portion, when the lid is closed and a beveled detent latch co-operating with the overhanging 80 wall to hold the lid in closed position and means for hinging the lid to the body portion at the side remote from said detent. 85

In testimony whereof I hereunto affix my signature.

NANNIE K. HUNT.
